UNITED STATES PATENT OFFICE.

HORACE E. WHITNEY, OF CAMBRIDGE, ASSIGNOR TO THE DOVER STAMPING COMPANY, OF BOSTON, MASSACHUSETTS.

MATCH-SAFE.

SPECIFICATION forming part of Letters Patent No. 544,018, dated August 6, 1895.

Application filed February 28, 1895. Serial No. 539,980. (No model.)

To all whom it may concern:

Be it known that I, HORACE E. WHITNEY, a citizen of the United States, residing at Cambridge, in the county of Middlesex and State 5 of Massachusetts, have invented a new and useful Improvement in Match-Safes, of which the following is a full, clear, and exact description, reference being had to the accompanying drawings, forming a part of this 10 specification, in explaining its nature.

The invention relates primarily to a match-safe having in suitable conjunction a pocket for matches and also a holder for the burned ends.

15 It also relates to a match-safe, made of tin or other suitable metal having these receptacles in juxtaposition and carried by a common support.

It also relates to the construction of a match-safe whereby the receptacle for burned matches is conveniently and cheaply arranged in relation to the pocket for good matches.

It also relates to a feature of construction whereby the parts constituting the safe are 25 joined or united together without the use of solder, so that they cannot be detached by the heat caused by burning matches.

The invention relates to other features of construction, which will hereinafter be more 30 fully described.

In the drawings, Figure 1 is a view in plan of one of the blanks from which the match-safe is made. Fig. 2 is a view in plan of the other blank used in its construction. Fig. 3 35 is a view of the blank of Fig. 1 partially completed. Fig. 4 is a section of the partially-completed safe upon the dotted line 4 4 of Fig. 3. Fig. 5 represents the blank of Fig. 2 partly formed. Fig. 6 is a section upon the 40 dotted line 6 6 of Fig. 5. Fig. 7 is a view in elevation of a removable burned matches or waste receptacle. Fig. 8 is a view in cross-section thereof. Fig. 9 is a view, enlarged, of the complete invention upon the dotted line 45 9 9 of Fig. 10; and Fig. 10 is a view in front elevation of the complete device. Fig. 11 is a view in front elevation of a complete match-safe having the features of my invention, showing two pockets for good matches instead 50 of one, as in Fig. 10. Fig. 12 is a view in rear elevation thereof. Fig. 13 is a view, partly in

cross-section and partly in plan, of the safe represented in Fig. 11. Figs. 14 and 15 illustrate the ends of the burned matches holder, Figs. 11, 12, and 13, which is not removable, 55 as in the case of Figs. 9 and 10. Fig. 16 is a horizontal section of that part of the device shown in Fig. 15.

My invention is illustrated as carried into effect in the following way:

A blank A of sheet metal, preferably tin, is formed of the shape represented in Fig. 1, and this is adapted to provide, when fashioned as hereinafter described, a back a to the entire device and also a back to the 65 match-pocket B. It also provides a bottom b to the match-pocket and a case c, which either forms the holder for the burned matches or acts to receive a separate receptacle, and to accomplish these results the blank A has formed 70 in it the holes c' near the bottom of that part which forms the back of the pocket B, and at one end the ears c² and the section of the blank between these holes and the ears is curved outwardly from the back, as represented in Fig. 9, and the ears extended through the holes c' and turned upon the back surfaces thereof, and there is thus provided the back and bottom of the match-pocket B and a space or holder for burned matches or for a 75 detachable receptacle C, in which they may be placed. In either event there is formed in the blank a wide recess or slot c³, which, when the blank is fashioned, is upon the upper side of the curved section at the front end of the 80 section b, which forms the bottom of the match-pocket. (See Fig. 9.) When a detachable receptacle for burned matches is used, I prefer to employ one of a shape to fit the cavity within said curved section—that is, a receptacle of cylindrical shape—and such a receptacle detached from its support is represented in Fig. 7. It comprises a circular shell c⁴, having closed ends c⁵ and a long recess or opening c⁶ in its side, corresponding in shape to 85 the recess c³ of the case. It is preferably of the same length as the cavity which holds it and fits it closely, and it is adapted to be removed therefrom by being moved endwise through it to afford means for emptying the 90 matches from it, and when in use its recess c⁶ is ordinarily in line with the recess c³. This 95 100

receptacle, however, is useful not only for holding the burned matches but also for safely holding unburned matches in traveling or at other times, as they may be placed in the receptacle C and the receptacle then turned sufficiently to close the recess c³, when they will of course be closely confined. (See Fig. 9.) When a removable receptacle is not used, the cavity itself may receive and hold the burned matches, and when so employed its ends are closed by suitable end pieces, one or both of which may serve as gates or doors, by means of which it may be emptied of its contents when necessary, and in Fig. 15 I have shown one of the ends as hinged at its inner end to the back section. One or both ends may be so closed, or one end may have a permanent piece attached to it to close it and the other end may be removable or open, as above specified.

The pocket for the good matches may be in one or two parts. I have represented both forms in the drawings, and in either case the pocket is formed from a flat blank E, the ends of which are united to the back of the case by ears e formed thereon, which extend through holes e' formed in the back, and which ears are bent up on the back. This flat blank is curved or bent to form ends, and its lower edge rests upon or is close to the section b of the case which forms its bottom.

The case-back may have a hole a', by which it may be suspended from a nail or other support, and it may also have a foot a², provided by an integral part of the frame formed or bent downward to provide a rest back of the center of the safe, (see Fig. 9,) by means of which it will stand securely without other support. The foot should not be as wide as the back of the frame, as otherwise the burned matches in the holder would be likely to fall out.

While I prefer to make the receptacle for the burned matches or the holder therefor and the bottom of the match-pocket and its back of one piece or plate or blank, because it has certain advantages in point of ease of construction, yet I would not be understood as limiting myself to this particular way of providing the desired result.

It will be seen that the invention comprises a pocket for unburned matches upon the upper side of a holder for burned matches, having a recess or opening through which the burned ends may be dropped into the holder; and that the two are combined to make an integral device.

There may be arranged in the blank, of which the case is largely made before it is bent into shape, a roughened section d, which in the complete article may be upon the lower front of the part which embraces the burned match or waste receptacle, and upon which matches may be struck or ignited.

Having thus fully described my invention, I claim and desire to secure by Letters Patent of the United States—

1. A match safe having a pocket for unburned or good matches and a holder containing a receptacle for burned matches the said holder having a recess or slot and the said receptacle being removable from the holder, and having a recess or slot corresponding to that of the holder, as and for the purposes described.

2. A match safe having a pocket for matches, and an attached cylindrical holder having a long opening in its upper part and a cylindrical receptacle contained in said holder and having a long slot or recess on one side thereof, and adapted to be turned in said holder.

3. A match safe having a pocket for matches and a holder for burned matches or for a receptacle for holding them, made from two pieces of sheet metal, one of which provides a back to the safe and forms the holder for the burned matches, or their receptacle, by being fashioned or turned upon itself so that its lower edge is united to its back, and thereby forming a bottom for a pocket for holding good matches, which pocket is completed by the attachment to the said formed blank of the second plate or blank which forms the sides and front of the said pocket, the said parts being united to each other by ears extending through slots or recesses in the part forming the back, which ears are bent upon the back, as and for the purposes described.

4. As an improved article of manufacture, a match safe made from two metal blanks A and E; the blank A having the small slots e' and c', the large slot c³, the tongues c² and the roughened surface d; the blank E being oblong in shape and having the tongues e, as and for the purposes described.

5. A match safe having a pocket for unburned matches and a receptacle for burned matches, having the foot a² made by turning down a portion of the back of the safe, substantially as described.

HORACE E. WIIITNEY.

In presence of—

F. F. RAYMOND, 2d,
J. M. DOLAN.
